UNITED STATES PATENT OFFICE.

HORACE D. MUNDAY, OF SCHENECTADY, NEW YORK.

TRUING DEVICE.

Application filed May 18, 1928. Serial No. 278,747.

This invention relates to a method and means of making true and keeping true the commutators and collector rings of electric machines, and in its preferred form has particular relation to a method and means of doing this while the machine is carrying its normal load, and of doing it automatically or with only nominal or casual attention.

From one cause or another the commutators and collector rings of many electric machines sooner or later get out of round. In the case of small machines the armature is usually taken out of the frame of the machines and the commutator turned in a lathe. The commutators of large machines are ground or turned with the armature in place. The apparatus now in general use for grinding such commutators comprises a base having thereon guides or ways, the base being set up on blocks on the floor or attached to some stationary part of the machine with the ways parallel to the commutator. On the base is mounted a carriage which, by means of a lead screw is moved parallel to the commutator. On the carriage is mounted a cross-feed slide which, by means of guides and screw is moved at right angles to the base of the apparatus, or in a radial direction to and from the commutator. On the cross-feed slide is mounted a small motor and grinding wheel, the small motor driving the grinding wheel. Instead of a grinding wheel, sometimes an abrasive block is used, the block being held in a tool post mounted on the cross-feed slide, like a lathe tool.

In operation of this grinding apparatus now in use, the small motor driving the grinding wheel is started. The cross-feed slide is then advanced by means of its screw till the revolving grinding wheel just touches the rotating commutator. The lead screw in the base of the apparatus is then turned, drawing the grinding wheel along the length of the commutator. The cross-feed slide is then advanced a thousandth of an inch or so towards the commutator, and the grinding wheel again moved along the length of the commutator. The operation is repeated till all the flat spots and ruts have been ground out of the commutator. Instead of the lead screw being turned by hand, often the lead screw is turned by another motor belted up to the pulley or handwheel of the lead screw, a switch thrown by hand being used to reverse this motor at each end of the commutator.

In the operation of the grinding device just described it is evident that the operator must be present throughout the entire operation which may consume from several hours to a day. It is generally necessary partly to dismantle the machine to enable the operator to position the grinding apparatus in proper operative relation to the commutator and it is also generally necessary to take off all or some of the useful load from the machine.

In employing the apparatus constructed in accordance with the present invention, I overcome the disadvantages just noted. In operation my improved apparatus is automatic and when initially adjusted and started it will continue the operation of grinding without further attention and will automatically stop after predetermined movement. In using the preferred form of my invention the apparatus may be applied to the commutator without dismantling or removing any of the parts of the machine and the machine may be kept in operation under full load during the entire grinding operation.

Numerous other advantages and objects of my invention will appear from the following description and explanation of the operation of my improved apparatus and method of grinding.

In a preferred embodiment, the invention comprises the abrasive mounted in some form of tool post or holder, means of advancing the abrasive toward the commutator or along the commutator, means for creating the force of some kind, which may be the spring, or weight or motor for causing the movement of the abrasive and means for hindering the motion for the abrasive, that is, a means which tends to retard or prevent motion of the abrasive toward or away from the commutator.

One effect of a hindering means employed by me is to prevent the abrasive advancing quickly into a low spot of the commutator as the low spot passes under the abrasive and to confine the rubbing of the abrasive to the high spots of the commutator. Or in case the abrasive does enter the low spot of the commutator the hindering means will offer a high resistance to the backward or retrograde motion of the abrasive as the abrasive is being pushed back by the commutator surface onto the high spot. In either of these cases the abrasive will bear more lightly on the low spots of the commutator than on other portion of the commutator surface, with the re-

sult that ultimately the commutator will be ground to a true cylindrical surface.

The hindering means which I employ may be frictional or it may consist of a viscous substance such as asphalt interposed between a stationary and movable part of the apparatus. Also, optionally, a sluggishly yielding metal such as lead or solder, may be employed. In certain cases to provide a hindering of the backward or retrograde movement of the abrasive, I may make use of the high resistance offered by a comparatively rigid grinding apparatus when the apparatus is caused to yield structurally a slight amount by the forcing backward of the abrasive by the high spot of the commutator. The weight of the grinding apparatus may contribute materially to this effect and if desired the apparatus may be weighted to increase its inertia.

The means of hindering the motion of the abrasive forms an important feature of the invention, together with the fact that the force for moving the abrasive is such that the advancement of the abrasive, radially at least, is harmlessly haltable on contact with the commutator.

With a viscous substance interposed to hinder the advancement of the abrasive towards the commutator, permitting the abrasive to move forward only slowly towards the commutator, the abrasive will slowly advance till it strikes the high parts of the revolving commutator. Since the speed of the commutator is so great in comparison with the slow speed of the abrasive that the abrasive is not able to feed forward into the low spots of the commutator while the commutator is making one revolution, it is evident that the low spots of the commutator will not be touched till all the high spots have been worn down. Consequently the commutator must necessarily become true.

In the use of friction hindering means for truing up a commutator there is the difference that in the case of friction both the high part and the low part of the commutator are worn down at the same time—the high part being worn down heavily and the low part lightly. In the case of the viscous substance hindering means, as has been seen, the low part of the commutator is not touched at all till the high part has been worn down completely. How friction can be used to true up a commutator can be seen from the fact that the net force causing the advancement of the abrasive is only the excess of the spring or weight over the friction hindering means. On the other hand the total force necessary to cause a retrograde movement of the abrasive is equal to the sum of the friction and the force of the spring or weight. Consequently the reaction pressure of the commutator on the abrasive will be much greater when the abrasive is

being shoved backward from the commutator than when the abrasive is merely stopped in its advancement towards the commutator. After the high level part of the commutator comes under the abrasive and the abrasive necessarily ceases any further retrograde movement, the slight spring in the apparatus and its supports as a whole may be made to cause the abrasive to continue to exert the maximum pressure on the level high part of the commutator. Consequently, since the abrasive exerts a heavy pressure on the high part of the commutator and a light pressure on the low part of the commutator, the commutator will finally become true.

Some of the metals or alloys have the property of yielding or bending slowly when subjected to a certain pressure. Lead is such a metal; solder is another. This property can be used in a number of ways to give a slow motion. For instance, a belt of lead or solder on pulleys will permit only a slow motion of the pulleys when the proper driving force is applied.

While in a preferred form of the invention the means used for hindering the motion of the abrasive are friction hindering means and viscous substance hindering means, sluggishly yielding metal and in certain cases relief springs, structural yield, inertia clock mechanism and an oil or other fluid pump.

In a preferred form of this invention for certain purposes, the present grinding apparatus in the general form just described is taken and adapted to automatic operation.

To make for simplicity the small motor driving the grinding wheel is eliminated. To make it unnecessary to remove the brush-holder arms, a long overhanging shaft or arm journaled in the cross-feed slide, carries at its extremity the abrasive or grinding member, and is preferably of a length to carry the abrasive completely across the commutator. The extremity of the arm is insulated from the main part of the arm which is surrounded by a fibre sleeve to avoid increasing the chance of a ground, or a flash-over between adjacent brush-holder sets.

The motor driving the lead screw is preferably retained. But to avoid the necessity of reversing this motor at short intervals at each end of the commutator, only one or a few traversing cuts are taken across the commutator, one cut at least however, being preferably of substantial depth. When the grinding device is in action the abrasive should preferably move from the inside end of the commutator to the outside end, and not the reverse. At the outer end of the commutator the abrasive should automatically stop and without the necessity of prompt attention by the operator. To increase the chance that the motor driving the lead screw of the device will stop when the abrasive reaches the outer

end of the commutator, a direct-current motor is used in what might be called a stallable manner. Some current-limiting means, such as a rheostat in the armature circuit, is used 5 to prevent any dangerous amount of current in the armature, though the motor may be indefinitely stalled or stopped with the current still in the armature.

Several devices are used to make sure that 10 the abrasive will not be carried beyond the end of the commutator, or beyond the shrink ring in the middle of the commutator, if the inner half of a commutator having a shrink ring is being trued. One device of this kind 15 is a push button mounted so as to be operated by the saddle or carriage of the truing apparatus and throw out the circuit breaker. Another device is a conical-ended nut clamped to the lead screw in the proper position to 20 open up the split nut attached to the saddle and throw it out of engagement with the lead screw when the abrasive has reached the desired limit of its travel. A third device is a clamp attached to the ways of the base of the 25 apparatus in position to block the travel of the saddle or carriage beyond the clamp.

To get a slow travel of the abrasive across the commutator some form of hindering means is used to hinder the motion of the 30 lead-screw. This hindering means should be of the delay type or at least include a hindering means of the delay type. The lead-screw may be thrown out of action (by opening up the split nut attached to the carriage) and the 35 saddle moved along the base by a direct pull; in this case friction hindering means could be used jointly with delay hindering means, but should preferably not be used alone.

Instead of using a hindering means of the 40 delay type to hinder the motion of the lead-screw, a train of worm gears and worms could be used between the small driving motor and the lead-screw, for the purpose of getting a very slow motion of the lead-screw as 45 compared to the motor speed.

To get the radial advancement of the abrasive towards the commutator as the abrasive travels along the length of the commutator from the inside end to the outside end of the 50 commutator, the means for advancing the abrasive radially towards the commutator may be operatively connected to the means for advancing the abrasive axially along the commutator, to the end that the radial advancement of the abrasive is proportional to 55 the axial advancement of the abrasive; or, if not exactly proportional, increasing as the axial advancement increases.

In certain cases the abrasive may be advanced radially by its own separate means and retarded by its own separate hindering means. In one preferred form of the invention the means of hindering the motion of the abrasive comprises friction hindering means 60 and viscous substance hindering means prin-

cipally, but also relief spring hindering means, the hindering means due to a sluggishly yielding or sluggishly distortable metal, such as lead or solder, as well as the hindering means due to the natural, structural yielding of the apparatus as a whole and its inertia. The weight to increase inertia may be embodied in the balance wheel of clock mechanism. Means are also provided to utilize a liquid to furnish hindering means of the 70 delay type for use in certain cases. It will of course be understood that for certain purposes any of these hindering means may be used alone.

The advancement of the abrasive which 80 may be an abrasive block or an abrasive wheel, radially towards the commutator may be brought about either by the rotation of the abrasive-carrying arm journalled in the cross-feed slide, or by the radial movement 85 of the cross feed slide itself, or by the base of the apparatus being slightly out of parallelism with the commutator. In this latter case the axial movement of the carriage will necessarily cause a proportional radial movement of the carriage and abrasive towards the 90 commutator.

The cross-feed slide may be operated by a screw mounted in bearing blocks attached to the carriage and in engagement with a two-part nut attached to the cross-feed slide. This screw and nut have a fine thread and a coarse thread, the fine thread being used when the cross-feed slide is to be advanced positively, and the coarse thread when the 100 cross-feed slide is to be advanced non-positively.

Provision is made in the apparatus for advancing the abrasive radially without at the same time advancing it axially. In this way 105 a local flat spot in the commutator can be trued up, or a "neck" cut in the inner end of the commutator or the outer end of the commutator cut down. If an abrasive wheel is used in this case means are provided so 110 that the wheel can be rotated by the lead-screw, the split nut attached to the carriage being thrown out of engagement with the lead screw so that no axial movement will be given to the abrasive wheel. Specific forms 115 of my apparatus wherein a rotary abrasive wheel is employed or other forms of abrasive, wherein the abrasive material is fed to the commutator in a direction, tangential thereto, form the subject matter of a copending application filed by me.

When asphalt is employed as a hindering means, say for the radial motion of the abrasive, it may be applied hot to the apparatus by smearing it on the surface of some part 125 which normally rubs against the surface of some other part; thus it may be applied to the surface of the cross-feed slide that normally slides along the carriage. When the asphalt is cool, the cross-feed slide can still 130

be moved but only comparatively slowly, the rate of motion under the action of a certain force, depending on the viscosity of the asphalt. While the asphalt is preferably applied hot it may be applied in the form of an asphalt paint, the solvent then being allowed to evaporate.

The asphalt may be so viscous at room temperature that it may require hours or days 10 for the part to move a fraction of an inch; or, on the other hand, in certain cases, it may be so soft that the eye can see the motion of the part. The principle of operation is that the radial advancement of the abrasive 15 will be so slow in comparison with the speed of rotation of the commutator that the abrasive will not have time to follow up into the low part of the commutator in the short time that is required for succeeding high part of 20 the commutator to go under the abrasive. It will thus be seen that in the operation of my improved method of grinding, there is a certain relation between the rate of advancement of the abrasive and the speed of rotation 25 of the commutator.

In the preferred form of my invention I provide means whereby the motion hindering means may be thrown out of action and the abrasive may be moved rapidly, without being hindered by the asphalt or other hindering means, so that, for example, the cross-feed slide may be manipulated by hand so as quickly to bring the abrasive into contact 30 with or near to the commutator, preliminary to automatic action.

It has been shown how a simple application 40 of delay hindering means of the viscous substance type to the apparatus for moving the abrasive, will enable such apparatus to operate automatically in truing a commutator. It has also been shown how the application of friction to such apparatus will enable this apparatus to operate automatically. In certain cases it is desirable to employ both 45 the friction hindering means and the viscous substance hindering means at the same time. It is to be noted that in the use of the particular friction means above described, the low spot of the commutator is always 50 ground, through lightly, as well as the high spot and in certain cases where it is desired to true up a commutator with a minimum of copper loss, the use of such hindering means alone might at times be objectionable. In using 55 delay hindering means merely of the viscous substance type non-positively, there is nothing to withstand the reaction thrust of the high part of the commutator against the abrasive except the resistance due to the viscosity of the asphalt, so that with soft asphalt or other soft viscous material there may be a slight yielding of the cross-feed slide or other movable part when the high part of the commutator comes under the abrasive. If however 60 we employ in the apparatus, both the

viscous substance hindering means and friction hindering means, it is clear the apparatus will not grind the flat spots of the commutator and consequently not cause unnecessary wearing of the commutator and at 70 the same time such apparatus, due to the viscosity of the asphalt and the friction will strongly resist the reaction thrust of the high parts of the commutator as they come under the abrasive so that the high spots will be 75 quickly and effectively ground down.

Numerous other advantages and objects of my invention will appear from the following description taken in connection with the accompanying drawing wherein:

Figure 1, is a perspective view, partly in section and partly broken away, of one form of apparatus constructed in accordance with my invention and showing the same applied to the commutator of an electric machine;

Figure 2, is a side elevation, partly in section, of the structure shown in Figure 1, together with the means for firmly securing such structure in position in proper relation 90 to the commutator;

Figure 3, is a top plan view of the structure shown in Figure 1;

Figure 4, is a sectional view taken on the line 4-4 of Figure 3;

Figure 5, is a sectional view taken on the line 5-5 of Figure 3;

Figures 6 and 7 are top and end elevations respectively, of the two-part nut employed as part of the feeding means;

Figure 8, is a sectional view taken on the line 8-8 of Figure 3 and showing in elevation the abrasive block and its holder;

Figure 9, is a diagrammatic view of a circuit control for a feeding motor;

Figure 10, is a diagrammatic view of a circuit control for an electrical heating means used to regulate the viscosity of asphalt employed for hindering motion of the abrasive;

Figure 11 is a detail view of a modified 110 abrasive member and its holder;

Figure 12 is a side elevation of a modified form of commutator truing apparatus applied to a dynamo electric machine commutator;

Figure 13 is a top plan view of another modified form of truing apparatus applied to a commutator.

Referring to the drawings, Figures 1-11 show a preferred form of the invention. On a longitudinal base 51 having ways or guides in the sides 52 of a dovetail tongue 53, is slidably mounted a carriage 54, with a complementary dovetail groove in its face fitting over the dovetail tongue 53 of the base. A lead screw 55 with suitable bearings in lugs 56^a and 56^b laterally projecting from either end of the base, and in engagement with the split nut 57 formed of parts 57^a and 57^b serves as the positive means of mov- 120 125 130

ing the carriage along the base 51; that is, parallel or generally parallel to the commutator when the apparatus is set up for grinding commutators.

5 The carriage 54 has on its upper face a dovetail tongue 58 at right angles to the base. Slidably mounted on the carriage 54 is the cross-feed slide 59; a complementary dovetail groove in its lower face fitting over the dovetail tongue 58 of the carriage. The cross-feed slide is moved along the carriage by a feed screw 61 mounted in bearing blocks 62 and 63 attached to the carriage. There are two threads of different pitches on the feed-screw and in the open-sided, two-part nut 64 with which it cooperates to move the cross-feed slide. This two-part nut, shown in detail in Figures 6 and 7, is reversibly attached to the cross-feed slide, so that either thread 10 may at will be brought into threaded engagement with the feed screw 61; the finer thread 65 when a positive or non-reversible motion of the cross-feed slide is desired and the coarser thread 66 when a non-positive or reversible motion is desired. In attaching this two-part nut to the side of the cross-feed slide there is secured by the screw 66^a between the cross feed slide and the two-part nut, a spacing member 67 with a complementary but 15 threadless semi-circular bore 68 facing and closing with a little clearance the open side of the open-sided two-part nut 64, the said nut being slidably secured to the cross-feed slide by the cap screws 69 through elongated 20 holes 69^a. Beyond the bearing block 62 extends for some distance a portion of the feed screw 61 threadless but of unreduced diameter, to the grooved hand-wheel 70, to which it is slidably secured by the key 70^a. Surrounding the outer part of the feed screw 25 between the bearing block 62 and the hand-wheel 70 is a pair of concentric tubes 71 and 72, the inner tube 71 being secured by the cap screws 73 through its flange 74 to the bearing block 62. The outer tube 72 is 30 optionally secured by the clamp 75 to the hub 76 of the hand-wheel 70. The hand-wheel is rotated by means of the solder wire or ribbon 77 wrapped around the hand-wheel, 70 and a weight 78 attached to the free end of the wire 77. Between the inner and outer tubes is a coating of asphalt 79 or other viscous substance to hinder the rotary motion of the outer tube on the inner tube. One 35 reason for using the sluggishly yielding solder wire 77 as a hindering means in addition to the hindering means of the asphalt 79 is to provide additional hindering means if the asphalt should become too soft—as by over-heating by the thermal controlling means—to function efficiently in a hindering way. If for instance the abrasive is being advanced towards the commutator by means of the cross-feed slide 59 actuated non-positively 40 by the coarse thread 66 of the feed-screw 61,

and without cooperating frictional hindering means, it is possible that very soft asphalt might permit a slight to-and-fro movement of the carriage that might prevent to some extent the most efficient truing of the commutator. On the other hand the coating of asphalt might be shattered by a sudden blow, the asphalt hindering effect being thus destroyed. With a slight rotary to-and-fro movement of the outer tube 72 due to the alternate coming under the abrasive of the low part and of the high part of the commutator, the shattered particles of asphalt might lack the quietness that is conducive to their proper knitting or coalescing. The use of the solder wire 77 will give the shattered particles of asphalt a better chance to knit, so that the asphalt soon can begin to function efficiently as a hindering means. The shattering of the asphalt might be due in part to a temperature too low for that particular grade of asphalt. The solder or lead wire however is not likely to be injured much in a hindering way by the ordinary changes of temperature.

Provision is made for a slight relief movement of the cross-feed slide 59 independent of the movement of the two-part nut 64 by the compression of one or the other of the relief springs 80. The screws 81 secure, 45 slightly swivelly, the inverted L-shaped plate 82 to the spacing block 67. Stiff spiral springs 80 are mounted on cap-screws 83 passing freely through plain holes in the plates 82 into threaded anchorage in the spacing block 67. The spiral springs are compressed to any predetermined initial stress by adjustment of the nuts 84. For the purpose of avoiding all lost motion between the plates 82 and the two-part nut 64 there are 50 four adjustment cap-screws 85, secured by the jam-nuts 86. By entirely compressing the springs 80 by screwing up the nuts 84 the relief action of the device is annulled, the plates 82 then being fixedly held against the 55 spacing block 67.

Attached to the bearing block 62 by the flexible support 98 is the electric lamp 99 in circuit with the current-controlling rheostat 100 and thermostat 100^a. The lamp 99 is 60 used to heat the asphalt 79 between the concentric tubes 71 and 72, thus controlling the viscosity of the asphalt 79 between the tubes 71 and 72, and consequently controlling the motion of one tube relative to the other. 65 Without the thermostat 100^a being in use, the heat received by the asphalt will depend on the distance of the lamp 99 from the tubes 71 and 72, and on the current in the lamp as modified by the rheostat 100, and by the degree 70 of interposition of the movable reflector 101 which may be rotated around the lamp socket 102 to partially or completely screen the tubes 71 and 72 from the lamp 99. Not all of these 75 means of control need be used at one time.

Further control of the movable tube 72 may be secured through varying the number of sections of the actuating weight 78 in use.

The upper part of the cross-feed slide takes the form of a clampable bearing block 111 in which is journalled the hollow shaft or arm 112 extending over the commutator 113 and ending in the reduced inner end or stud 114 to which is secured the abrasive member 115. Cap screws 131 are used to set up the bearing cap. Screws 132 threaded into the bearing cap and bottoming on the lower half of the bearing are used to adjust the bearing, as by preventing any possible spring in the bearing cap from gripping the arm 112 too closely. A strip of felt 133 in the slotted opening in the bearing prevents the entrance of abrasive powder and copper chips to the bearing. Surrounding the outer part of the arm 112, is a pair of telescopic tubes 116 and 117, which, with the coating of asphalt 118 between them constitutes one of the means of hindering the rotation of the arm 112. The inner tube 116 by means of the cap screws 119 through holes 25 in the tube flange 121 is attached to the lower half of the bearing block 111. The outer tube 117 is optionally clamped by the clamp 122 to the collar 123, which is adjustably secured to the arm 112 by the set screw 124 set up 30 against a copper disc to prevent the marring of the arm 112. The hindering effect of the asphalt coating is modified by controlling its viscosity, which is in turn controlled by the heat received from the electric lamp 125, this 35 heat depending on the position of the lamp by flexure of the adjustable support, or by the adjustable interposition of the shade rotatable around the lamp socket to act as a screen between the lamp 125 and the tubes 116 and 117, or by controlling the current in the lamp by 40 means of a rheostat or thermostat.

On the opposite end of the bearing block 111 is a friction hindering means. On the arm 112 between the end of the bearing block 45 111 and the worm gear 141 is a grooved and loosely fitting collar 142. This collar fits somewhat loosely on the key 143, which also serves together with the set screw 144, to secure the worm wheel 141 to the arm 112. 50 This set screw 144 with its inner end imbedded in a depression in the key 143 serves also to keep the key 143 assembled with the worm-wheel 141 whenever the arm 112 is moved axially to another position in the bearing block 111. There is no keyway in the arm 112. The length of the key beyond the 55 face of the worm-gear and towards the bearing block 111 is slightly longer than the thickness of the collar 142, thus serving as a convenient spacing member whenever the arm 112 is moved axially in the bearing block, the end of the key being brought up against the end of the bearing block 111. The collar 142 may 60 conveniently have a few thousandths of an

inch or more clearance both in the bore and 65 in its keyway.

Partly surrounding the collar 142 and positioned in the groove thereof is the clamp 146, the two members of which 147 and 148 are clamped together by the cap-bolt 149. The 70 clamp member 147 has threaded in its upper end the stud 150 to which is swivelly secured, by the thumb-screw 151 the bracket 152, to which is adjustably attached the bar, 153 bearing the weight 154 of one or more sections 75 154^a and 154^b, and which are slidably adjustable on said beam, to which they are secured by the set-screws 155. The beam has a right-angled end member 155^a on which it may rotate being then secured by the set-screw 155^b. 80 This end member 155^a may be used for securing the beam 153 to the bracket 152 when it is necessary to clear some obstruction, such as a bearing; in which case bolts 156 and 157 are used to secure the right-angle end member 85 155^a. In each of the two clamp members 147 and 148 is a threaded hole 158 and 159 of a size to receive the threaded end of the stud 150. By this means the stud 150 can always be positioned in a vertical or generally 90 vertical direction regardless of whether the apparatus is set up with one side or the other at the bottom, as may be desirable in some cases. Gauge 160 aids in determining the angular position of the arm 153. 95

The object of having the beam 153 swivelly adjustable on stud 150 is to divide the pressure effect of the weight 154 into two components, one component tending to rotate the arm 112 and the other component tending to prevent the rotation of the arm by causing friction between the collar 142 (loosely keyed to the arm 112) and the adjacent end of the bearing block 111. This can be seen more clearly if the two extreme positions of the beam 153 be considered. If the beam is in a position at right angles to the arm 112, it is evident that there will be no tipping of the collar 142 and consequently no friction between the collar 142 and the end of the bearing block 111. Hence, in this position, all the effect of the weight will be spent in rotating the arm 112 and none in hindering the rotation of said arm. The other extreme position of the beam 153 is that parallel to the arm 112. In this extreme position it is evident that there will be no tendency of the weight 154 to produce rotation of the arm 112, the only effect of the weight being to tip the collar 142, cause friction between the collar 142 110 and the end of the bearing block 111, and thus hinder, or rather prevent, the rotation of the arm 112. Between these two extreme positions, on the one hand of all rotary effect and 115 no hindering effect, and on the other hand of all hindering effect and no rotary effect, there must be some middle position where the rotary effect will just overcome the hindering 120 effect. 125

effect. This position, or one somewhat nearer that of maximum rotary effort, will generally be the more desirable position in which to keep the beam 153. This position 5 can be easily found, if not marked on the apparatus, by loosening the clamp 122 on the tube 117 to eliminate the viscous substance hindering effect, and then slowly swinging around the weighted beam 153, from an initial position parallel to the arm 112, till the arm begins to move. If the bearing cap is not set up tight enough to give a clamping effect, the position so found will be independent of the weight 154 or its position on the 15 beam 153. Under these conditions the rotary effect of the weight 154 on the arm 112 and the friction hindering effect on the arm 112 will increase or decrease together, the latter being a certain percentage of the former. 20 This percentage can be changed by moving the beam 153 to a new position.

From what has been said it is evident that by loosening the clamp 122 the arm 112 may be rotated against a friction hindering effect 25 only; or by tightening up on the clamp 122 and keeping the beam 153 at right angles to the arm 112 the arm 112 may be rotated against a viscous substance hindering effect only; or with the beam in an intermediate 30 position, both the friction hindering effect and a viscous substance hindering effect will be in operation together. It may be noted that by tightening up the cap screws 131 to grip the arm 112 a little another friction 35 hindering effect is available; this friction effect does not vary with the angular position of the beam 153.

In the methods that have been described for advancing the abrasive member either 40 by the advancement of the cross-feed slide 59 or by the rotation of the arm 112, the means of advancement of the abrasive member have been independent of the movement of the carriage. Means are provided however for 45 advancing the abrasive proportional, or substantially proportional, to the movement (axial) of the carriage 54. Attached to the lug 56^a laterally projecting from the base 51 of the apparatus, by the cap screws 171, is the 50 strap 172, swivelly securing by the cap screw 173 one end of the round bar guide 174, the other end of which is vertically adjustable and securable by the thumb-screw 175 slide- 55 able in the slot 176 of the strap 177 swivelly secured by the cap screw 178 to the lug 56^b projecting laterally from the base of the device. Gauges 178^a and 178^b aid in securing the proper slope of the round bar guide 174. Sliding on the round bar guide 174 is the 60 slotted shoe 179 adjustable as to clearance by the screws 180. Integral with the shoe 179 is the vertical stud 181, which forms a pivotal support for the block 182 with a capped bore 183 that slidingly receives the rod 184 thread- 65 ed into the member 148 of the clamp 146.

The reason for having this round bar guide 174, slightly adjustable vertically (thus throwing it slightly out of parallelism with the arm 112 and the base 51 of the apparatus) is to advance the abrasive member 115 enough, 70 as it is carried along the length of the commutator 113, to make up for the wear on the abrasive. This guide is intended for use with an abrasive block rather than with an abrasive wheel. The guide can be thrown out of 75 action to a limited extent by loosening the thumb-screw 175; or it may be thrown completely out of action by unscrewing the outer half of the rod 184 from the coupling nut 184^a, or by releasing the rod 184 from the 80 block 182 by taking out the screws 185 and removing the cap 186.

A still simpler way to advance the abrasive is to set up the apparatus with the base 51 slightly out of parallelism with the axis of the 85 commutator 113, the body of the abrasive coming progressively nearer the commutator as it travels along the length of the commutator, the endeavor being to advance the body of the abrasive to the approximate extent that 90 will result in a cylindrical commutator rather than in one slightly tapering.

Provision is made for another means of advancing the abrasive proportional to the movement of the carriage along the length of 95 the commutator. This means consists in an operative geared connection between the worm gear 141 and the lead screw 55, the latter being the driving member, and forming, through the coarse thread 187, in reality a 100 long spiral gear meshing with the spiral gear 188 secured by the set screw 189 and the key 190 to shaft 191 driving the gear unit 192 and 193 secured thereto by the set screw 194, one gear 192 of said gear unit optionally 105 meshing with the gear 195 of the shiftable gear unit 195—196, which is securable and slidably adjustable by a set screw and key on the shaft 199. Shaft 199 has suitable bearings in the sides 200 and 202 of the gear housing 200—201—202, (201 being the base supporting the sides) and is flexibly coupled by the coupling 203—204 to the shaft 205 driving the worm 206 slidably secured thereto by the keyway 207, said worm 206 meshing with 110 the worm gear 141 attached to the arm 112 carrying the abrasive member. Preferably the thread and teeth of the worm 206 and worm gear 141 are of such a pitch that the worm gear 141 can not act as a driver to drive 115 the worm 206. The shaft 205 has suitable bearings in the bearing lugs 208 and 209 projecting from the base or plate 210, the latter being secured to the side of the cross-feed slide by the screws 211. By removal of the bearing caps 213 by unscrewing the screws 214, and by taking out the coupling screws 215, the shaft 205 and worm 206 may be easily removed from the apparatus. The worm 206, 120 by means of a short key in the worm, is 125 130

splined on the shaft 205. The purpose of removing the worm 206 is to make it possible to drive the arm 112 independently of the worm 206, using instead of the worm a motor 5 to drive the pulley 216. However, if the thread and teeth of the worm 206 and worm gear 141 are of such a pitch that the worm gear will drive the worm, then it will not be necessary to remove the worm 206 when 10 the arm is rotated by means of a motor and the pulley 216. In this latter case the spiral gear 188 should be shifted on the shaft 191 till it is out of engagement with the lead screw 55. Another means of rotating the arm 112 independently of the lead screw 55 is by using 15 a motor to drive the shaft 191. The operative connection between the driving motor and the shaft 191 may preferably take the form of a telescopic shaft, with a universal coupling at 20 either end of this telescopic shaft to make connection to the shaft 191 and to the motor shaft. When the shaft 191 is driven in this way, the spiral gear 188 will be shifted out of engagement with the lead screw 55. The gear 25 housing 200—202 is attached by the screws 216^a through the base 201 to the lug 216^b projecting from the end of the carriage 54.

As said before, the gear unit 195—196 is shiftable, and when shifted from the position 30 as seen in Figure 4 to the right as far as possible, the gear 195 is taken out of mesh with gear 192, and gear 196 comes into mesh with the intermediate gear 217 which is always in mesh with the gear 193 of the gear unit 35 192—193. This shifting of the gear unit 195—196 serves to reverse the direction of rotation of the arm 112. The intermediate gear 217 rotates on the stud 219 anchored by a set screw in the gear housing side 200.

40 As said before, the lead screw 55 has suitable bearings in the lugs 56^a and 56^b laterally projecting from the ends of the base 51. The reduced end 220 bearing in the lug 56^a, together with the collar 221 secures the lead screw 55 against axial motion. The other 45 and outer end of the lead screw 55 projects for some distance beyond the outer lug 56^b; the extremity of said lead screw having mounted thereon the grooved hand-wheel 222 50 securable and slidably adjustable on said shaft by the set screw 223 and soft metal disc, said hand-wheel being grooved to receive a belt 225 from the driving motor 226, or cord from a driving weight. The hand-wheel 222 55 has on the inner side a notched hub 227 adapted to engage the notched outer end 228 of the outer one of a pair of concentric tubes 229 and 230 surrounding that part of the lead screw coming between the lug 56^b and the hand-wheel 222, the inner tube 229 being secured by 60 its flange 231 and the screws 232 to the side of the bearing lug 56^b. Between the two tubes 229 and 230 is a coating of asphalt 233, which serves to hinder the motion of one tube 65 relative to the other. The amount of this

hindering depends on the viscosity of the asphalt, and the viscosity of the asphalt depends on its temperature, which in turn depends on the amount of heat received from the electric lamp 234, the amount of heat received depending on the nearness of the lamp or adjustment of its flexible support, or by the degree of interposition of the shade rotatable on the lamp socket, or by the current in the lamp 234 as modified by a rheostat. 70

The lead screw has two threads 187 and 239, the coarser thread 187, as said before, making of the lead screw practically a long spiral pinion and being operatively connected to the worm gear 141 to drive the arm 112, 80 carrying the abrasive 115. The finer thread 239 of the lead screw is, through engagement with the split nut 57, used to move the carriage along the base 51. The two halves of the split nut 57 are in the form of U-shaped members 57^a and 57^b, which are swivelly secured by the pins 240 through the extremities of the U limbs to the lug 241 projecting from the end of the carriage 54. The two halves 57^a and 57^b of the split nut 57 are kept in threaded 85 engagement with the lead screw 55 by means of the spiral spring 242 hooked over the two screws 243, a screw being in each half on the split nut 57. To throw the split nut 57 out of engagement with the lead screw 55 there is provided the conical knurled nut 244 threaded onto the cap screw 245, the latter being fixedly threaded into the lug 241; entrance thereto for the cap screw 245 being secured through the hole 246 made up of the juxtaposition of two semicircular grooves in the near limbs of the U-shaped members 57^a and 57^b. By turning the conical knurled nut 244 to the right it is evident that it will advance into the hole and separate the two halves of the split nut 57 and throw them out of engagement 95 with the lead screw 55.

On the lead screw 55 there is provided a similar conical nut or conical bushing 247 for the purpose of automatically throwing the split nut 57 out of engagement with the lead screw 55. A short portion of the thread in the near side of the split nut is bored out and the corner of the hole slightly enlarged to furnish easy entrance to the point of the conical nut 247. The nut is secured by the thumbscrew 249. This conical nut serves as an automatic stop to limit the motion of the carriage 54. By securing the conical nut 247, in any desired position on the lead screw the carriage 54, will automatically stop when the split nut 57 comes into engagement with the conical nut 247, although the lead screw itself continues to turn. 110

115 Provision is made for a non-positive advancement of the carriage by means of a stranded wire cord 261, one end being secured by the screw 262 to the carriage 54, the cord extending therefrom through the hole in the block 263 around the pulley 264 120

pivoted in the slotted end of the block 263, thence at right angles to its former direction around the tube 230, the end of the cord being secured to the tube by the screw 265. By 5 moving the pulley 222 into notched engagement with the tube 230, and with the split nut 57 out of engagement with the lead screw 55, rotation of the pulley 222 by the motor 226 will wind up the cord 261 and move 10 the carriage parallel to the commutator. Instead of throwing the split nut 57 out of engagement with the lead screw 55, the set screw 223 in the hub of the hand-wheel 222 may be backed off and the hand-wheel allowed 15 to revolve on the end of the lead screw as a spindle. The movement of the carriage may be hindered by the asphalt alone, as in the way just given, or by the oil pump alone or by both together. With the use of a 20 stranded wire cord to give a direct pull to the carriage the viscosity of the asphalt can generally be made low enough to give as much speed to the carriage as is desired. If the set-screw 223 is set up while the hub 227 25 is still in notched engagement with the tube 230 the hindering effect of the oil pump is added to that of the asphalt to any amount desired by properly regulating the discharge valve to restrict the discharge of the oil. If 30 it is desired to cut out the asphalt hindering means when the carriage is moved by a direct pull, the screws 232 may be removed, thus allowing the inner tube 229 to rotate with the outer tube.

35 To support the lead screw 55 there is a grooved step 267, an extension of the block 268, the latter being attached by the screws 269 to the underside of the lug 216^b projecting from the end of the carriage 54. This 40 support is intended to keep the lead screw 55 from springing out of mesh with the gear 188 when the split nut 57 is not in engagement with the lead screw 55, and consequently 45 is not itself forming incidental support to the lead screw 55.

For mounting the abrasive member there is provided the hollow stud 272 forming a part of the arm 112 but insulated from the main part thereof and removably pressed 50 into an enlarged bore in the main part of arm 112. Within the bore is the split metal tube 273. Within the metal tube is the insulating tube 274 cemented thereto. Within the insulating tube 274 is the thin split metal 55 tube 275 cemented to the insulating tube 274. There is an insulating washer 276 at the bottom of the enlarged bore abutting on the supporting conical metal washer 276^a; and in front of this insulating washer is the protecting metal washer 277. The hollow stud 272 is driven into the enlarged bore 278, insulated as just described; but for additional security there are three countersunk set screws 279, which bottom in slight depressions in the split tube 273.

The part of the stud 272 extending beyond the end of the main part of arm 112 has a square external thread 280. On this threaded part is an accurately fitting bushing 281 slidably keyed to the stud 272 by key 282. 70 The bushing 281 has a square external thread, but no internal thread. Threaded on the extreme end of the stud 272 is the nut 283 circumferentially grooved at 284 to receive one end of the spiral spring 285, the other 75 end of the spring 285 abutting on the end of the bushing 281. Between the other end of bushing 281 and the main part of arm 112 is the spring 285^a. The purpose of the bushing and springs is to give a slight axial 80 movement of relief to the abrasive when a commutator having both deep ruts and end play is being trued up, thus preventing the abrasive member from being caught in a rut and broken or having the active end sheared 85 off by the axial movement of the commutator. Generally there is no necessity to take precautions against end play, so that a split bushing may be used instead of the sliding bushing 281; or the clamp 286—286^a or abrasive wheel 287 may be secured directly to the stud 272. By screwing up the knurled nut 283 till it abuts against the end of the bushing 281 and entirely compresses spring 285^a the axial movement of the bushing 281, 90 and therefore of the abrasive member 115 or 287, relative to the main part of arm 112 may be prevented. Before assemblage these springs 285 and 285^a should preferably be put into a state of partial compression, the 100 two washers and the attaching chains serving to keep the spring partially compressed, but offering no hindrance to further compression by the abrasive when a combination of an engaging rut and end play of the armature give an axial movement to the abrasive independent of the rest of the apparatus.

The bushing 281 is provided also with an external keyway 288, Figure 8, which, together with the thread 288^a, is made use of 110 when, instead of an abrasive block, an abrasive wheel 287 is used as the abrasive member. This keyway 288, an engaging key and a complementary keyway in the collar 291 (as seen in Figure 11) serve to prevent the 115 collar 291 from rotating on the bushing 281, and therefore diminish the possibility of the abrasive wheel 287 getting loose and rotating on the bushing 281 after the said abrasive wheel has been tightly clamped against the 120 face of the collar 291 by the nuts 292.

Surrounding the main part of the arm 112, that overhangs the commutator when in operation, is a plurality of telescopic insulating sleeves 293^a—293^b made of such material 125 as fibre or Herkolite. The object of the insulating sleeves is to diminish the possibility of the arm 112 being the cause of a ground or short circuit on the commutator. If holes are drilled in the end of the insulating sleeve 130

293^a for the purpose of inserting the counter-sunk set screws 279 or for inserting a wrench, then a short section of insulating sleeve 293^c is used to cover up the holes to prevent the possibility of current getting into the arm through these openings. The insulating washer 295 insulates the end of the main part of arm 112.

When the abrasive member is in form of an abrasive block a double member clamp 286—286^a as shown in Figure 8, is used to secure the abrasive block 115, to the stud 272. One end of the clamp member 286 is circular and is clamped by the cap screws 297 around the 15 slideable bushing 281 or around a substituted split bushing or around the stud 272, the latter two arrangements somewhat diminishing the chance of vibration or chattering of the abrasive member. The other clamp member 20 286^a is U-shaped, and, by the cap screws 298 is clamped around the abrasive block 115. Strips of fibrous material 299 cemented to the 25 extreme ends of the limbs of the U-shaped clamp member 286^a, serve to soften and distribute the gripping stress of the clamp member on the abrasive member 115, and at the same time to bring the gripping contact line as near as possible to the active end of the abrasive member 115. Insulating sheets 300 and 300^a of fibre or Herkolite protect to a considerable extent the accidental contact of the clamp with a charged part of the electric machine. Over the head of the cap screw 298 is an insulating cap 301 with a threaded stem 302 integral with the cap and screwed into the threaded hole in the head of the cap screw. The cap 301^a is threaded onto the opposite end of the cap screw 298.

In Figures 1, 2 and 3 are shown means for 40 stopping the motion of the carriage after a predetermined travel. As shown in Figure 3 a clamp 332 is attached to the dovetail tongue 53 of the base 51; the clamp 332 being adjustable to different positions along the 45 base 51 and being adapted to be secured in any position by means of the cap screw 332^a. At the upper side of the clamp 332 is a push button 333 in position to be struck and operated by the carriage or some part attached 50 thereto or prominently projecting therefrom, such as the bearing block 62. Operation of the push button 333 breaks the current in the holding magnet coil 333^a trips the circuit breaker 333^b and cuts off current from the 55 motor 226 driving the pulley 222. In case the push button 333 should fail to function the bearing block 62 after a very small additional movement strikes the clamp 332 bringing the carriage 54 to a halt. Although in 60 this case the current may not be cut off from the motor, the resistance in the rheostat 333^c is so large that the motor 226 can be stalled indefinitely without harm.

To limit the movement of the cross-feed 65 slide, there is provided an offset bracket 361,

the lower end 362 thereof being attached by the cap screws 363 to the face of the carriage 54 and the other end 364 apertured to slidingly receive the body of the cap screw 366 fixedly threaded into the cross-feed slide 59. 70 The limit of the movement in either direction of the cross-feed slide will be determined by adjustment of the knurled nuts 367 in relation to the bracket end 364.

Means of limiting the rotation of the arm 75 112 include a stud 371 with its lower end threaded into the cross-feed slide 59. Splined on the said stud is the split clamping block 372, adjustable and securable on said stud by the knurled thumb-screw 373. One 80 end of the block 372 overhangs the rod 184, and in this end is the knurled-headed temper screw 374 positioned vertically over the center of the rod 184. It is evident that when the rod strikes the temper screw 374 it will 85 come to a stop, and consequently also the clamp 146 and the arm 112 to which the clamp 146 is secured. Adjustment of the clamp 146 on the arm 112 with reference to the distance of the rod 184 from the temper screw 374 90 will permit a greater range to the rotation of the arm 112.

Another means of limiting the rotation of the arm 112 is provided by the limit bar 375 secured to the top of the bearing block 111 by 95 the screws 376 and 377, on the latter of which the said bar may swivel slightly. When the set screw 124 in the collar 123 strikes the limit bar 375, the rotation of the arm 112 is halted. By adjusting the position of the collar 100 rotatively any degree of rotation of the arm 112 not greater than one complete revolution can be secured.

Current for the motor 226 is supplied from mains 334 and 335, through switch 336 and 105 fuses 337. From one pole of the switch, say the positive, the current passes by the wire 338 to the circuit breaker 333^b. From the circuit breaker 333^b three wires lead. Current passes by one of these wires to the rheostat 110 333^c thence by wire 342 to the reversing switch 343, thence by wire 344 or 344^a to the motor armature 345. From the circuit breaker 333^b a second wire 346 leads to one terminal 347 of the motor field 348. A third part of the 115 current passes through the retaining magnet coil 33^a thence by wire 350 to the push button 333. From the negative pole of the switch 336 three wires lead. Current passes by one of these wires 351 to the reversing switch 343, 120 thence by either wire 344^a or wire 344 to the motor armature 345. A second wire 353 leads to the terminal 354 of the motor field 348. A third wire 355 leads to the push button 333.

The asphalt between the tubes 116 and 117 125 used to hinder the motion of the arm 112 may lose its effect either from a high temperature or from a low temperature and excessive strain. This has been explained at length in the case of the asphalt used to hinder the mo- 130

tion of the feed-screw of the cross-feed slide. To take care of this contingency in the case of the arm 112 there is provided a simple clock mechanism 377^d with its driving wheel 377^e 5 geared to the worm-gear 141 that drives the arm 112. From the clock escapement there extends vertically the rod 377^f to which is attached the horizontal arm 377^g bearing the adjustable weights 377^h, the distance of which 10 from the rod 377^f determines the rate of movement of the clock mechanism and therefore of the rate of rotation of the arm 112 and therefore of the rate of movement of the abrasive 115 towards the commutator. The clock escapement is preferably of the kind that will 15 function when the driving wheel rotates in either direction.

If the clock escapement is the kind that will operate only in a forward direction and locks 20 in the other direction, then we would have positive hindered (delayed) advancement of the abrasive.

To provide for the possibility that the asphalt hindering the motion of the lead-screw 25 55 may lose its hindering effect there is a small oil pump 377^k operatively connected to the lead-screw 55 at its inner end, with a valve 337^l to regulate the rate of discharge of the oil and therefore the rate of rotation of the 30 lead-screw and therefore of the carriage 54 and therefore the axial movement of the abrasive 115. Where a positive movement of the carriage with comparatively high speed 35 is desired, thus necessitating the use of the fine thread of the lead-screw with comparatively high rate of rotation of the lead-screw, the oil pump may be used as a hindering means in preference to comparatively soft asphalt, which might be more or less erratic in 40 its hindering effect when very soft.

In view of the foregoing the operation of the truing device is readily understood. As explained before, the apparatus, in preparation for grinding a commutator, is mounted 45 on an offset flat bar beam secured by studs in the bearing box of the electric machine. The base of the apparatus is secured to the lower step of said offset flat bar beam. Further security is attained against vibration by 50 the use of jack-screws supporting the base of the apparatus and the flat bar beam, and by turn-buckle guy rods or chains running from the flat bar beam and the base of the apparatus to the base of the pillow-block. The base of the apparatus is mounted parallel 55 to the axis of the commutator except in the case where it is desired to advance the abrasive towards the commutator by having the base of the apparatus slightly out of parallelism with the axis of the commutator.

The lead screw 55 is then turned by hand or by a motor until the abrasive member reaches the inner edge of the commutator. A clamp 441 is then clamped across the ways 60 of the base and against the inner end of the

carriage to serve as an automatic stop thereafter to limit the inward movement of the carriage.

The lead screw is then turned in the other direction until the abrasive member reaches 70 the outer limit of its travel. If there is a shrink ring in the middle of the commutator this will determine the outer limit of travel while the inner half of the commutator is being trued up. The several safety devices 75 to limit the outer travel of the carriage are now adjusted; these include the clamp 332, the push button 333 attached thereto, and the conical bushing 247 for throwing the split nut 57 out of engagement with the lead 80 screw 55. The endeavor should be to so regulate the push button by adjusting its position on the clamp 332 that it will function to throw out the circuit breaker slightly before the carriage is compelled to stop by the clamp 332 85 or conical bushing 247.

By loosening up the clamp 122, the arm 112 can be rotated without the interference of the asphalt hindering means.

The carriage is then run toward the inner 90 end of the commutator again till it strikes the clamp 441 and stops. During these to-and-fro movements of the carriage, the rheostat 333^e should be manipulated a bit and the position of the rheostat handle noted 95 that will give a few pounds of pull on the pulley 222.

Clamps 122 and 75 are loosened, freeing 100 respectively the arm 112 and the feed screw 61 from the effects of the asphalt hindering means. By rotation of the arm 112 or movement of the cross-feed slide the abrasive member is brought into contact with the commutator. If the abrasive member is an abrasive block the endeavor should be to have the 105 abrasive make contact with the commutator, not in a radial line, but at a substantial angle to a radial line, say 45° with a radial line, as there will be less chance of the abrasive chattering in this latter case. The abrasive 110 block should preferably be in a "trailing" position; that is, the commutator should leave from the acute angle of the abrasive block. If the electric machine runs in both directions a still larger angle is desirable.

For a time the abrasive may be fed towards the commutator without any axial movement of the abrasive. This feeding or advancement of the abrasive towards the commutator 115 may be made by the rotation of the arm 112 by means of the beam 153 and weight 154. The clamp 122 is tightened up, thus clamping the tube 117 to the collar 123 on the arm 112. The lamp 125 is now brought into use if necessary to soften up or lower the viscosity of the 120 asphalt 118 between the tubes 116 and 117, thus permitting a slow rotation of the arm 112. How fast the arm 112 will rotate and advance the abrasive towards the commutator 125 will depend on the magnitude of the actuating 130

weight 154, its leverage on the beam 153 as well as on the viscosity of the asphalt; also on the grade of the abrasive block, the area of contact with the commutator and the condition of the contact end. Where there is little reason for speed in finishing the job, the abrasive block may be advanced towards the commutator no more than $1/64$ of an inch an hour. By advancing the abrasive very slowly it is used much more efficiently than in ordinary grinding practice, say two to five times more efficiently—referring to the weight of copper ground off for each unit of weight of abrasive material consumed. It is generally advisable, at least at first, to use only the softer grades of abrasive—say grades "F", "G", and "H", according to the grading system used by most manufacturers of abrasives. A soft abrasive is not so liable to pick up copper, and then cease to cut—particularly when the force advancing the abrasive is small. And a small advancing force is desirable not only for economy of abrasive material, as has been said, but also for lessening the chance of vibration in the apparatus—particularly when the foundation for the grinding apparatus is not as firm as it might be. Generally the abrasive block should be as short as possible so that the active end of the abrasive block will be as close as possible to the arm 112, so as to lessen the chance of vibration.

In the operation of the apparatus as just explained both friction hindering means and viscous substance hindering means are in operation to hinder the motion of the arm 112. The beam 153 bearing the weight 154 has been in a position other than at right angles to the arm 112, so that there is considerable friction of collar 142 on the end of the bearing block to hinder the rotation of the arm 112.

To operate with asphalt hindering means alone, all that is necessary to do is to swing the beam 153 around till it is at right angles to the arm 112, thus eliminating the tipping of the collar 142 against the end of the bearing block 111 and consequently the friction of the collar against the end of the bearing block.

To operate with a friction hindering effect only the clamp 122 is loosened, thus eliminating the asphalt hindering effect. To find the best position for the beam 153 the beam is swung around from an initial position parallel to the arm 112 till the arm 112 begins to move, the angular position of the beam with reference to the arm 112 being noted on the gauge 160. A few degrees beyond this will generally be the most desirable position for the beam 153. The amount of the weight 154 or its leverage will not alter the relation between the rotary effort and the friction hindering effect if this angle is not changed and if the arm 112 turns freely in the bearing block 111. There will be a slight to-and-fro

rotary movement to the arm 112 because the abrasive block will follow up the flat spots in the commutator. If the commutator is in bad shape—as with flat spots blackened up from high mica—and immediate improvement is wanted, then friction hindering means should be used alone to advance the abrasive block radially. After allowing the abrasive to act for a time at the inner end of the commutator the axial travel of the abrasive block may start, using the stranded wire cord 261 instead of the lead screw 55 to move the carriage. Non-positive means of advancing the carriage are somewhat more desirable in this case, with ridges and ruts assumed to be in the commutator, than the positive means through the use of the lead screw. If the edge of the abrasive should be in contact with the side of a ridge a sudden starting of end play might break off the abrasive block unless a retrograde movement of the carriage is possible as is the case with a non-positive means such as the cord 261. While the slideable bushing 281 and the springs 285 and 285^a are intended to take care of end play, the possibility of a backward movement of the carriage gives additional security that no harm will be done by end play.

Descriptions of other methods of operating the device follow. Where there is the necessity for the arm 112 to clear a shrink ring in the middle of the commutator or a commutator fan guard on the outer end of the commutator, the active end of the abrasive block may have to be from four to six inches from the center of the arm 112. Abrasive wheels should be small as possible in diameter to minimize chance of vibration. Thin and narrow abrasive blocks may be used to avoid vibration when the foundation of the apparatus is not very secure.

To limit the advancement of the abrasive block the temper screw 374 is adjusted, allowing the abrasive block to advance, say $1/3$ of an inch before the rotation of the arm 112, is brought to a halt.

During this process the rod 184 is out of operative engagement with the round bar guide 174, and the worm 206 out of engagement with the worm wheel 141.

Having now cut a shallow groove in the inner end of the commutator, the next strip is to carry a traversing cut across the commutator. Preliminary to this the rod 184 is put into operative engagement with the round bar guide 174, the grooved hand-wheel 222 belted to the motor, into notched engagement with the tube 230 and the split nut 57 into engagement with the lead screw 55, and the stranded wire cord 261 removed from operative connection between the carriage 54 and the outer tube 230. If necessary the lamp 234 is used to modify the viscosity of the asphalt between the tubes 229 and 230. The round bar guide is then given sufficient inclination

by adjustment of its outer end by means of the thumb-screw 175 to cause the abrasive to wear away, say 1/2 inch, while it is making the traversing, or axial cut, along the length 5 of the commutator. When adjusting the end of the round bar guide, reference may be had to the two gauges 178^a and 178^b adjacent to the slot 176 in the strap 177. The gauge on the right 178^a indicates the number of degrees 10 of rotation of the arm 112 for one foot of travel of the carriage 54. The gauge on the left 178^b indicates the number of inches of wear of the abrasive block for one foot of travel of the carriage. In marking this latter gauge the average length of the abrasive block and its clamp from the center of the arm 112 to the active end of the abrasive is assumed to be five inches; and the average inclination of the abrasive block with a radius 15 is assumed to be 45°. When the length of the abrasive block and its clamp, and the angle it makes with a radius vary from these assumed conditions, allowances can be made accordingly.

25 In getting rid of the copper chips and abrasive dust an exhaust fan may be made use of (if such a fan is available), the suction hose being connected to the outer end of the hollow arm 112, the suction intake being through the hollow stud 272. To facilitate the entrance of the grinding débris into the hollow stud 272, a sheet of asbestos cloth may be folded around the abrasive block 115 and the stud 272 to form a common hood to confine the débris therein as well as form a passageway to the hollow stud. If there is no exhaust fan at hand a gentle stream of air from the compressed air system may be allowed to play upon the abrasive block as near as possible 30 to the inner end of the commutator, in order to drive the débris outward and keep it out of the commutator risers. The compressed air hose may be attached to the hollow arm 112, the air striking deflectors as it leaves the hollow stud 272 which throw it against the abrasive block and drive the abrasive and copper dust away from the armature winding.

35 A simple compressed air ejector may be made out of a short piece of old rubber hose. Through a hole or slot near the middle of the short piece of rubber hose is inserted the nozzle of the compressed air hose, the nozzle extending some inches up one branch of the short piece of rubber hose.

40 How fast the carriage 54 will travel will depend partly on the viscosity of the asphalt between the tubes 229 and 230 as modified by the heat from the lamp 234, partly on the torque of the motor 226 as regulated by the rheostat 333^c, partly on the inclination of the round bar guide 174, as well as on the size and grade of the abrasive block itself and the condition of the commutator. If there are no high ridges in the commutator the abrasive 45 may advance axially 1/4 inch to an inch or more an hour; if there are high ridges that have to be ground away from their sides to a considerable extent, and if it is desired to use the abrasive block as efficiently as possible, then the abrasive block may be advanced axially considerably less than 1/4 of an inch an hour. Generally when there are high ridges on a commutator a second cut will have to be taken, so the first cut, or roughing cut, can be taken regardless of the possibility of vibration of the apparatus. In this case a hard abrasive block can be used and a greater torque put on the motor 226 by adjusting the rheostat 333^c.

50 In the operation just described it was assumed that the brush-holder sets were far enough apart to permit the entrance between them of the abrasive block inclined at a suitable angle to a radius. However the brush-holder sets may be so close together that the abrasive block has to be positioned on a radial line. In this case we are prohibited from rotating the arm to advance the abrasive block, being limited to either the use of the cross-feed slide or to setting up the apparatus 55 with the base out of parallelism with the axis of the commutator; the former means being applicable to advancement of the abrasive radially with or without a coexisting axial travel of the abrasive, while the latter means— 60 the base of the apparatus out of parallelism with the axis of the commutator—is applicable to a radial advancement of the abrasive only in coexistence with an axial advancement of the abrasive. It is possible of course 65 to use the cross-feed slide with the hose out of parallelism with the axis of the commutator.

70 With the abrasive block at the inner end of the commutator, we may first advance the abrasive radially without any axial movement, using for this purpose the cross-feed slide. To turn the feed-screw 61, the weight 75 with several turns of solder wire 77 around the hand-wheel 70 is employed, utilizing if 75 necessary the lamp 99 to lessen the viscosity of the asphalt 79 between tubes 71 and 72. The clamp 75 is tightened up, thus clamping the hub of hand-wheel 70 to the outer tube 72. One of the knurled nuts 367 is adjusted to set 80 a limit, say of 1/8 of an inch, to the advancement of the abrasive. During the operation just described the motor 226 is not in use. The motor 226, together with the other accessory means as previously described is now 85 put into operation to drive the lead screw 55. To permit the radial advancement of the abrasive while it is making its axial movement along the commutator, we may back off the knurled nut 367 that stopped the movement of the cross-feed slide, to the amount of, say one inch. Judgment is now used as to the proper weight to be applied to the hand-wheel 70 and the proper viscosity of the asphalt 90 79 between the tubes 71 and 72 to ad-

vance the cross-feed slide approximately one inch while the abrasive traverses the length of the commutator, erring on the side of too little advancement rather than too much. 5 However, instead of using the cross-feed slide to advance the abrasive one inch during its axial travel from the inner end of the commutator to the outer end of the commutator, the apparatus may be set up with the base slightly 10 out of parallelism with the axis of the commutator, so that the outer end of the commutator is one inch nearer the base than is the inner end. Consequently, when the abrasive block reaches the outer end of the 15 commutator it will have advanced one inch; and in any intermediate position its radial advancement will have been proportional to its axial advancement.

Let us assume another condition which it 20 is desired to remedy. After some years of use the commutator has developed at its inner end a shoulder with a large fillet at its base. The shoulder is objectionable in that, in conjunction with end play, it may strike 25 a brush on the side and break it; or may prevent the brush holder being brought near enough to the commutator to allow a proper feeding of the brush. The fillet is also objectionable in that, when a new brush is in- 30 serted in the brush holder nearest the fillet, it keeps most of the brush from touching the commutator until the brush has worn to a fit, only the inner corner of the brush touching the commutator on the fillet. Even when 35 the brush has worn to a fit the end play of the armature causes the fillet to wedge the brush out of contact with the commutator for a considerable part of the active end of the brush at more or less frequent intervals. To remedy this condition it is desired to cut back 40 the shoulder a bit and eliminate the fillet almost entirely. An abrasive wheel, slowly rotating, will accomplish this purpose very well. The abrasive wheel may be rotated by 45 the lead screw 55 through the chain of gears operatively connecting the lead screw and the worm gear 141 on the arm 112. The split nut 57 is thrown out of engagement with the lead screw 55 to prevent motion of the 50 carriage 54. The clamp 146 is removed so as to permit complete rotation of the arm 112. The lead screw 55 is driven and regulated in the manner previously described. To advance the abrasive wheel radially the cross- 55 feed slide is used in the manner previously described. If desired the clamp 75 may be loosened, thus eliminating the hindering effect of the asphalt between the tubes 71 and 72 on the feed screw 61, one of the knurled 60 nuts 367 being adjusted to permit only a limited advancement of the cross-feed slide. It is evident that, as the relatively thin abrasive wheel slowly rotates, the unworn square cornered contour of the perimeter of the 65 abrasive wheel is constantly being brought

into active contact with the shouler and fillet on the commutator, thus insuring a square shoulder. If the work is not finished in one revolution of the abrasive wheel, the wheel can be reversed and the unworn square contour of the other side of the wheel brought into action for a second revolution of the wheel. If two revolutions of the abrasive wheel are not enough to square up the shouler and eliminate the fillet, a traversing cut 70 may be taken with the wheel along the length of the commutator, this operation tending to true up the abrasive wheel. Or the wheel may be taken off the apparatus and trued up with a diamond point or other truing device. 75 If it is desired to limit the rotation of the abrasive wheel to one complete revolution, the collar 123 secured to the arm 112 by the set screw 124 is so adjusted in reference to the limit bar 375 that the set screw 124 strikes 80 the said limit bar 375 after one complete revolution. In the operation just described the asphalt hindering means may be in action on both the lead screw 55 and on the arm 112, or on one only; if on one only it is 85 preferable that this one should be on the arm 112. As previously stated the construction and method of operation of a grinding apparatus wherein the abrasive is moved tangentially to the commutator, and new abrasive surface is constantly being presented to the commutator, forms the subject matter of 90 a copending application filed by me.

In the explanation of the operation of the truing apparatus up to this point the hindering means—both friction hindering means and viscous substance hindering means—have acted in both directions; that is, they have acted to hinder the forward motion of the abrasive and to hinder the backward motion of the abrasive. The force concerned in the advancement of the abrasive might be called a force of medium magnitude. In the method of operation about to be explained the hindering means acts in only one direction—to hinder a backward motion of the abrasive; and the force concerned in the advancement of the abrasive might be called a force 105 of small magnitude.

This form of hindering means includes 110 the two stressed springs 80, which hinder the motion of the cross-feed slide 59 in either direction from a certain central position. While this device serves as relief means to permit a slight backward motion of the abrasive under certain possible conditions (such as the stopping of the electric machine at night with the abrasive block overhanging a deep flat spot in the commutator, the settling of the abrasive block into the flat spot 115 during the night by the gradual yielding of the asphalt on the tubes on the arm 112 or on the feed screw 61, and the starting of the electric machine in the morning without first backing the abrasive block out of the flat 120 125 130

spot on the commutator) it also serves as hindering means to hinder a backward motion of the abrasive block. To employ this form of hindering means to the best advantage the force advancing the abrasive should be just large enough to bring the abrasive block into contact with the commutator, but the force should act through positive means, such as the fine thread 65 on the feed screw 61, or through the worm gear 141 on the arm 112. Another way of securing, for this purpose, the positive advancement of the abrasive radially is setting up the apparatus with the base slightly out of parallelism with the axis of the commutator. Considering the operation of either form of positive advancing means, without the use of any asphalt hindering means or any special friction hindering means, let it be assumed that a small force acting through positive means brings the abrasive block into contact with the commutator. The first contact of the abrasive block with the commutator may be made at a high part of the commutator; if such is the case the advancement of the abrasive will temporarily halt till a low spot of the commutator comes under the abrasive block, when the abrasive block will creep forward a little more. When the next high spot of the commutator comes under the abrasive block, the abrasive block can not back off the way it was advanced, because the means of advancing the abrasive is assumed to be positive means; the only other way for the abrasive block to back off is through the compression of one or the other of the springs 80. When the next low spot on the commutator comes under the abrasive block the weak actuating force is able to advance the abrasive block a little deeper into the low spot of the commutator. When the next high spot of the commutator comes under the abrasive block one of the springs 80, will have to be compressed still more, causing greater abrasive action on the high spot of the commutator. Continuing to advance the abrasive block a little at each revolution of the commutator the comparatively weak force will finally succeed in getting the abrasive block into contact with the bottom of the low spot of the commutator. At this point the advancement of the abrasive is brought to a halt except as the end of the abrasive wears away. There is very little wear by the abrasive on the bottom of the low spot of the commutator, because the force bringing forward the abrasive was made small enough to bring the abrasive block into only harmlessly haultable contact with the commutator. Consequently the abrasive block grinds off the commutator very little at the bottom of the low spots, but very heavily at the high spots.

Just how heavy the abrasive action is on the high spots of the commutator depends

on the stiffness of the springs 80; and this stiffness can be easily regulated by adjustment of nuts 84 as previously explained. Consequently, with the flat spots of the commutator being worn away very little and the high spots very much the commutator must finally become true. It may be noted that the accidental and unavoidable inertia of the moving parts tends to prevent the some aid in the truing process, as the inertia of the moving parts tends to prevent the abrasive block from following up entirely to the bottom of the low spots of the commutator. In fact, in certain cases by the use of inertia alone, if the inertia is sufficiently great a commutator can be trued up.

A relief spring may also be employed in conjunction with the abrasive clamp 286 and 286^a and the bushing 281 to which the clamp 286 and 286^a is clamped. By making the keyway in the bushing 281 a little larger than the key 282, the bushing and the clamp will have a slight rotary motion relative to the stud 272. A stiff spiral spring with its ends anchored to the stud and the clamp may be used to rotate the clamp to the amount of the keyway clearance, and in a direction opposite to that in which the reaction of the commutator tends to rotate the abrasive and the clamp 286 and 286^a. By advancing the abrasive block positively but lightly into harmlessly haultable contact with the flat spots of the commutator, the reaction thrust of the high spots of the commutator against the abrasive and the stiff spiral spring just mentioned will cause heavy wear on the high spots of the commutator; so the commutator will finally become true, as explained more in detail in connection with the relief springs 80.

195

In another general way of using hindering means to true up a commutator, the hindering means acts to hinder the advancement of the abrasive but not the backward motion of the abrasive. This means includes the studs 371 and the split clamping block 372 splined thereon and adjustable and securable by the knurled thumb-screw 373. One use of these elements has been explained before—that in which they serve to limit the advancement of the abrasive member. In that case the split clamping block 372 was tightly secured to the stud 371 by the knurled thumb-screw 373. If now the thumb-screw 373 is set up only tight enough to nearly but not quite stop the rotation of the arm 112 when actuated by the weight 154, the commutator can be trued up by this form of hindering means alone. To eliminate the asphalt hindering means the clamp 122 is loosened and to eliminate other friction hindering means the beam 153 on which is mounted the weight 154 is positioned at right angles to the arm 112. The weight 154, comparatively speaking should be large,

120

125

130

since the weight alone, without any help from the hindering means, has to withstand the reaction of the high spots of the commutator tending to drive the abrasive member backwards. The abrasive action on the high parts of the commutator may be made as great as desired by increasing the weight 154. And this without any increase of abrasive action on the flat spots of the commutator, provided the friction of the clamping block 372 is properly increased by adjustment of the thumb-screw 373; always having the friction of the clamping block 372 just a little less than that necessary to prevent the weight 154 from rotating the arm 112. Since the flat spots will be ground lightly and the high spots heavily, the commutator will finally become true. The abrasive member may of course have at the same time an axial movement as well as the radial movement if desired; the actuating means of the axial movement being under the control of the asphalt hindering means as previously explained.

While in an axial movement of the abrasive provision is generally made for a radial advancement of the abrasive to compensate for the wear of the abrasive during its travel between the outer and inner end of the commutator, this radial advancement can of course be omitted when desired. If the abrasive is in the form of an abrasive wheel that slowly rotates as it moves axially, unworn parts of the perimeter of the abrasive wheel are continually coming into contact with the commutator, so that the commutator should be trued up to a cylindrical form without any radial advancement of the abrasive. The truing of the commutator by a slowly rotating grinding wheel is more fully explained in a copending application filed by me. If a light finishing cut is being taken across the commutator, particularly with a hard abrasive, radial advancement of the abrasive may be omitted.

Use of friction hindering means exacting a friction somewhat in excess of that above described may also result in the desired delayed movement. Suppose that the actuating force is not quite able to overcome the friction hindering means when the electric machine is stationary. When the machine is in operation, however, there is or may be enough vibration to help the actuating force to slowly overcome the friction and advance the abrasive. If there is no vibration in the electric machine artificial vibration could be introduced in the form of a small air rapper or vibrator or electric "buzzer."

In Figures 12 and 13 I show two modified forms of truing device which embody certain of the principles of my invention and are of relatively simple construction. These truing devices are particularly adapted for truing the commutators of small electric ma-

chines wherein a bearing of the machine is housed in an end shield or bearing bracket 502 (Figure 12) attached to the machine by four cap screws 503. For the purpose of mounting the device shown in Figure 12, the lower two cap-screws are removed and considerably longer ones 505 and 506 substituted. Tubes 508 and 509 are mounted on these long cap-screws 505 and 506 and tightly set up thereby against the machine frame. This is for the purpose of giving rigidity to the apparatus; increased rigidity may be given by supports under the outer ends of the cap-screws. The abrasive member 510 is mounted on the arm 512 under the commutator 513, one end of said arm being swivelly attached by the screw hook 514 and thumb-nut 516. On the other tube 509 is mounted a cam 517, which, as it rotates raises the abrasive block 510 into contact with the commutator 513. To rotate the cam 517 there is clamped to its hub 518, by the cap-screw 519, the clamp 520 actuated by the weight 521 adjustable on the stud 522 by the set-screw 523. To limit the advancement of the abrasive, a chain 524 with turnbuckle adjustment 525 runs from the upper cap-screw 503 to the weight 521, the amount of initial slack in the chain 524 determining the amount of advancement of the abrasive block 510.

In operation of the modification shown in Figure 12 the cam 517 acting under the influence of the weight 521 is constantly urging the abrasive member 510 into contact with the commutator. If the gradient of the cam 517 is steep it will turn backward when the high spots of the commutator come in contact with the abrasive block 510 and the arrangement will form a friction hindering means. The pressure exerted by the low spot of the commutator to stop the advance of the abrasive block will depend on the torque exerted by the weight 521 minus the torque due to the friction of the cam 517. The force exerted by the high spot of the commutator to force the abrasive block backwards will depend on the torque exerted by the weight 521 plus the cam friction torque. The excess of the latter over the former will cause the high spots to be worn away faster than the low spots; so the commutator will finally become true.

If the gradient of the cam 517 is so gentle that the cam does not slip or turn backward when the high spot of the commutator comes into contact with the abrasive block, the arrangement will form a means for positively advancing or feeding the abrasive into harmlessly haultable contact with the commutator and reliance will be had on the structural yielding of the apparatus to furnish the hindering effect.

The form of invention shown in Figure 13 may be considered as a modification of that

shown in Figure 12 wherein the cam 517, clamp 520, weight 521 and tube 509 are removed, a conical tube 526 substituted for the tube 509, and between the end of the conical 5 bushing and head of the cap-screw is secured the expanded and apertured end of the pulley spindle 527; a cord 528 being provided which leads from the end of the arm 528^a over the pulley 529 to the weight 530. The outer edge 10 of the arm 528^a is cut away a bit at 531 to give a more substantial or central area of contact between the conical tube and the arm 528^a. The hole in the conical tube is not central, but is parallel to one of the elements of the 15 cone. The adjustable clamp 528^b serves to limit the lateral motion of the arm 528^a and the abrasive member 532. It will be seen that the form of the screw hook 533 allows both a vertical rotation and a lateral rotation 20 of the arm 528^a.

The operation of this modification is easily understood. The purpose of this modification is to sweep the abrasive block 532 axially under the commutator and grind away the 25 ridges as well as the high spots of the commutator. As the arm 528^a carrying the abrasive block 532 is drawn by the weight 530 axially along under the commutator, the arm and the abrasive block advance at the same 30 time towards the commutator, due to the conical bushing 526. By rotating this conical bushing to the proper position any degree of vertical movement of the abrasive can be secured from a horizontal movement to that of 35 the maximum possible.

Various other hindering means may be easily added to this modification. For instance, the pulley 529 may be removed and the cord 528 allowed to run over or around 40 the spindle 527 for $\frac{1}{4}$ turn or for $1\frac{1}{4}$ turns, thus introducing friction snubbing hindering means. Or a band or wire of a slowly deformable metal such as lead or solder may be substituted for the cord 528 and allowed to 45 run over the pulley 529 or spindle 527. Or the spindle may be smeared with asphalt to hinder the motion of the pulley, thus introducing viscous substance hindering means, which may of course, if desired, act cooperatively with the deformable metal hindering 50 means.

Other forms of the generic invention herein disclosed are described in my copending applications K, L, M, N, O, P and Q, 278,748 to 55 278,754 respectively, all of even date herewith.

Having now described my invention what I claim and desire to secure by Letters Patent is:

60 1. A truing or grinding device, particularly for commutators, comprising an abrasive member, or active member, means of causing the advancement of the abrasive member to cooperating contact with the rotating commutator, means of directing the 65 advancement of the abrasive member towards the

advancement of the abrasive member towards the commutator, means of hindering motion of said member, and means of mounting the device on something stationary and in position to coact with the rotating commutator. 70

2. A truing or grinding device, particularly for commutators, comprising an abrasive member, or active member, means of causing the advancement of the abrasive member to cooperating contact with the rotating commutator, means of directing the advancement of the abrasive member towards the commutator, means of hindering motion of said member, thermal means for controlling the effect of said hindering means, and means of mounting the device on something stationary and in position to coact with the rotating commutator. 75 80

3. A truing or grinding device, particularly for commutators, comprising an abrasive member, or active member, means of causing the advancement of the abrasive member to cooperating contact with the rotating commutator, means of directing the advancement of the abrasive member towards the commutator, means of hindering motion of said member, electrically generated thermal means for controlling the hindering means, and means of mounting the device on something stationary and in position to coact with the rotating commutator. 85 90 95

4. A truing or grinding device, particularly for commutators, comprising an abrasive member, or active member, means of causing the advancement of the abrasive member to cooperating contact with the rotating commutator, means of directing the advancement of the abrasive member towards the commutator, means of hindering motion of said member, means of mounting the device on something stationary and in position to coact with the rotating commutator, and means of limiting the advancement of the abrasive member to a predetermined amount. 100 105

5. A truing or grinding device, particularly for commutators, comprising an abrasive member, or active member, means of causing the advancement of the abrasive member to cooperating contact with the rotating commutator, means of directing the advancement of the abrasive member towards the commutator, viscous substance means of hindering the motion of a moving part of the device, thermal means of modifying or controlling the viscous substance hindering 110 means, and means of mounting the device on something stationary and in position to coact with the rotating commutator. 115 120

6. A truing or grinding device, particularly for commutators, comprising an abrasive member, or active member, means of causing the advancement of the abrasive member to cooperating contact with the rotating commutator means of directing the advancement of the abrasive member towards the 125 130

commutator, viscous substance means of hindering motion of said member, and means of mounting the device on something stationary and in position to coact with the rotating commutator.

7. A truing or grinding device, particularly for commutators, comprising an abrasive member, or active member, means of causing the advancement of the abrasive member to cooperating contact with the rotating commutator, means of directing the advancement of the abrasive member towards the commutator, a viscous substance, as asphalt, interposed between a stationary and moving part to hinder the motion of the latter and consequently of the abrasive, and means of mounting the device on something stationary and in position to coact with the rotating commutator.

20 8. A truing or grinding device, particularly for commutators, comprising an abrasive member, or active member, actuating means of causing the advancement of the abrasive member to cooperating contact with the rotating commutator, means of directing the advancement of the abrasive member towards the commutator, means of hindering motion of said member, said hindering means consisting of friction hindering means, and means of mounting the device on something stationary and in position to coact with the rotating commutator.

35 9. A truing or grinding device, particularly for commutators, comprising an abrasive member, or active member, actuating means of causing the advancement of the abrasive member to cooperating contact with the rotating commutator, means of directing the advancement of the abrasive member towards the commutator, means of hindering the motion of a moving part of the device, said hindering means consisting of a weight attached 100 to a moving part of the device to increase the inertia, and means of mounting the device on something stationary and in position to coact with the rotating commutator.

40 10. A truing or grinding device, particularly for commutators, comprising an abrasive member, or active member, actuating means of causing the advancement of the abrasive member to cooperating contact with the rotating commutator, means of directing the advancement of the abrasive member towards the commutator, means of hindering the motion of a moving part of the device, said hindering means consisting of friction hindering means and viscous substance hindering means and means of mounting the device on something stationary and in position to coact with the rotating commutator.

45 11. A truing or grinding device, particularly for commutators, comprising an abrasive member, or active member, actuating means of causing the advancement of the abrasive

member to cooperating contact with the rotating commutator, means of directing the advancement of the abrasive member towards the commutator, yieldable relief or hindering means, permitting a retrograde movement of the abrasive when a certain contact pressure of the abrasive with the commutator has been exceeded, and means of mounting the device on something stationary and in position to coact with the rotating commutator. 75

12. A truing or grinding device, particularly for commutators, comprising an abrasive member, or active member, actuating means of causing the positive advancement of the abrasive member to harmlessly haltable contact with the commutator, means of directing the advancement of the abrasive member towards the commutator, yieldable relief or hindering means, permitting a retrograde movement of the abrasive member when a certain 85 contact pressure of the abrasive with the commutator has been exceeded, and means of mounting the device on something stationary and in position to coact with the rotating commutator. 90

13. A truing or grinding device, particularly for commutators, comprising an abrasive member, or active member, actuating means of causing the advancement of the abrasive member to cooperating contact with the rotating commutator, means of directing the advancement of the abrasive member towards the commutator, means of hindering the motion of a moving part of the device, said hindering means consisting of a weight attached 100 to a moving part of the device to increase the inertia, and means of mounting the device on something stationary and in position to coact with the rotating commutator. 95

14. A truing or grinding device, particularly for commutators, comprising an abrasive member, or active member, actuating means of causing the advancement of the abrasive member to cooperating contact with the rotating commutator, means of directing the advancement of the abrasive member towards the commutator, means of hindering the motion of a moving part of the device, said hindering means consisting of a sluggishly yieldable metal, such as lead or solder, operatively 110 connected in the mechanism, and means of mounting the device on something stationary and in position to coact with the rotating commutator. 115

15. A truing or grinding device, particularly for commutators, comprising an abrasive member, or active member, actuating means of causing the advancement of the abrasive member to cooperating contact with the rotating commutator, means of directing the advancement of the abrasive member towards the commutator, means of hindering the motion of a moving part of the device, said hindering means consisting of friction hindering means that automatically increases the 120

125 130

- frictional hindering effect as the magnitude of the actuating force is increased, and automatically decreases the frictional hindering effect as the magnitude of the said actuating force is decreased, means of varying the ratio 5 that the said friction bears to the said actuating force, and means of mounting the device on something stationary and in position to coact with the rotating commutator.
16. A truing or grinding device, particularly for commutators, comprising an abrasive member, or active member actuating means of causing the advancement of the abrasive member to cooperating contact with the rotating commutator, means of directing the advancement of the abrasive member towards the commutator, means of hindering the motion of a moving part of the device, said hindering means consisting of friction hindering 15 means that automatically increases the frictional hindering effect as the magnitude of the said actuating force is increased, and automatically decreases the frictional hindering effect as the magnitude of the said actuating 20 force is decreased, and means of mounting the device on something stationary and in position to coact with the rotating commutator.
17. A truing or grinding device, particularly for commutators, comprising an abrasive member, or active member, means for causing the advancement of the abrasive member to cooperating contact with the rotating commutator, means for hindering such 25 advancement, means for moving the abrasive member along the commutator and means for mounting the device on something stationary and in position to coact with the rotating commutator.
18. A truing or grinding device particularly for commutators, comprising an abrasive member, or active member, means for causing the advancement of the member into cooperating contact with the commutator, a 30 body of sluggishly yielding material interposed between a relatively movable and relatively stationary part of the device to hinder motion of said member and means for mounting the device on something stationary 35 and in position to coact with said rotating commutator.
19. A truing or grinding device particularly for commutators, comprising an abrasive member, or active member, means for causing the advancement of the member into cooperating contact with the commutator, means for moving said member along said commutator, a body of sluggishly yielding material interposed between a relatively movable and relatively stationary part of the device to hinder motion of said member and means for mounting the device on something stationary 40 and in position to coact with said rotating commutator.
20. A truing or grinding device, particu- 45 larly for commutators, comprising an abrasive member, or active member, means for causing the advancement of the abrasive member to cooperating contact with the rotating commutator, means comprising a viscous substance for retarding a moving part of the apparatus to hinder the advancement of the abrasive member toward the commutator, and means for mounting the device on something stationary and in position to coact with the rotating commutator.
21. A truing or grinding device, particularly for commutators, comprising an abrasive member, or active member, actuating means for causing the advancement of the abrasive member to cooperating contact with the rotating commutator, friction hindering means for retarding the advancement of the abrasive member towards the commutator and means for mounting the device on something stationary and in position to coact with the rotating commutator.
22. The method of truing a commutator which consists in holding an abrasive member against the surface of the commutator 50 rotating the commutator while the member is so held and pressing said member against the surface of the commutator with a relatively high pressure while the high spots of the commutator are passing under the abrasive member and with relatively low pressure while the low spots of the commutator are passing under the abrasive.
23. A truing or grinding device, particularly for commutators, comprising an abrasive or active member adapted to be held in cooperating contact with said commutator, means for moving said member during the grinding operation and means for hindering motion of said member, consisting of two relatively movable parts having adjacent concentric cylindrical surfaces and a viscous substance interposed between said surfaces.
24. A truing or grinding device, particularly for commutators, comprising an abrasive or active member adapted to be held in cooperative contact with said commutator, means for moving said member during the grinding operation and means for hindering motion of said member consisting of two relatively movable parts having adjacent concentric cylindrical surfaces and asphalt interposed between said surfaces.
25. A truing or grinding device, particularly for commutators, comprising an abrasive or active member adapted to be held in cooperating contact with said commutator, means for moving said member during the grinding operation, means for hindering motion of said member and means for rendering said hindering means inoperative so as to permit rapid motion of said member.
26. A truing or grinding device, particularly for commutators, comprising an abrasive or active member, adapted to be held

in cooperating contact with said commutator, means for moving said member during said grinding operation, means for hindering motion of said member consisting of a rotary part movable with said member and formed with an outer cylindrical surface, a second part formed with an inner cylindrical surface adjacent to and concentric with said first named surface, a viscous substance interposed between said surfaces and releasable means for holding said second part stationary.

27. A truing or grinding device, particularly for commutators, comprising an abrasive or active member adapted to be held in cooperating contact with said commutator, means for moving said member radially of said commutator, means for moving said member axially of said commutator and releasable means for hindering either or both of the radial and axial movement.

28. A truing or grinding device, particularly for commutators, comprising an abrasive or active member adapted to be held in cooperating contact with said commutator, means for moving and hindering the movement of said member during said grinding operation, said means comprising a rotary shaft, a fixed tube, a second tube surrounding and releasably secured to said shaft and telescoping loosely said fixed tube, and a viscous material interposed between the said two tubes.

29. A truing or grinding device, particularly for commutators, comprising an abrasive or active member adapted to be held in cooperating contact with said commutator, means for moving and hindering the movement of said member during the grinding operation, said means comprising a rotary shaft, a stationary support, a tube releasably attached thereto, a tube surrounding and releasably securable to said shaft and telescoping loosely said first named tube, and viscous substance means interposed between said two tubes, said securing and attached means permitting both tubes to rotate together or to remain stationary together or one tube to rotate relative to the other tube.

30. A truing or grinding device, particularly for commutators, comprising an abrasive or active member adapted to be held in cooperating contact with said commutator, means for moving and hindering the movement of said member during said grinding operation, said means comprising a rotary shaft, a tube cooperating with said shaft, and a viscous material interposed between said tube and shaft.

60 31. A truing or grinding device, particularly for commutators, comprising an abrasive or active member adapted to be held in cooperating contact with said commutator, means for moving and hindering the move-

ment of said member during said grinding operation, said means comprising a rotary shaft, a tube surrounding said shaft, a viscous material interposed between said tube and shaft, and means for clamping said tube to a stationary support, said means being releasable so as to permit said tube to turn with said shaft.

32. A truing or grinding device, particularly for commutators, comprising an abrasive or active member, means for advancing said member toward and maintaining said member in position to cooperate with said commutator, means for moving said member, and permitting said member to yield, axially of said commutator, during grinding.

33. A truing or grinding device, particularly for commutators, comprising an abrasive or active member, means for advancing said member toward and maintaining said member in position to cooperate with said commutator, and means for causing the movement of said member axially of said commutator during the grinding operation and means for guiding the axial movement of said member so that as said member moves axially it approaches said commutator.

34. A truing or grinding device, particularly for commutators, comprising an abrasive or active member, means for advancing said member toward and maintaining said member in position to cooperate with said commutator, means for causing the movement of said member axially of said commutator, during the grinding operation, means for hindering said axial movement and means for guiding the axial movement of said member so that, as said member moves axially, it approaches said commutator.

35. A truing or grinding device, particularly for commutators, comprising an abrasive or active member, means for advancing said member toward and maintaining said member in position to cooperate with said commutator, means for causing the movement of said member axially of said commutator during the grinding operation and means for guiding the axial movement of said member to cause said member to move toward said commutator to compensate for wear of the abrasive and means for adjusting said guiding means so as to vary ratio of said last named movement to said axial movement.

36. A truing or grinding device, particularly for commutators, comprising an abrasive member, or active member, actuating means of causing the advancement of the abrasive member to cooperating contact with the rotating commutator, means of directing the advancement of the abrasive member towards the commutator, fluid means that operatively hinders the motion of a moving part of the mechanism, and means of

mounting the device on something stationary and in position to coact with the rotating commutator.

37. A truing or grinding device, particularly for commutators, comprising an abrasive member, or active member, actuating means of causing the advancement of the abrasive member to cooperating contact with the rotating commutator, means of directing the advancement of the abrasive member towards the commutator, liquid means that operatively hinders the motion of a moving part of the mechanism, and means of mounting the device on something stationary and in position to coact with the rotating commutator.

38. A truing or grinding device, particularly for commutators, comprising an abrasive member, or active member, actuating means of causing the advancement of the abrasive member to cooperating contact with the rotating commutator, means of directing the advancement of the abrasive member towards the commutator, fluid pressure means for hindering the motion of a moving part of the device, and means of mounting the device on something stationary and in position to coact with the rotating commutator.

39. A truing or grinding device, particularly for commutators, comprising an abrasive member, or active member, actuating means of causing the advancement of the abrasive member to cooperating contact with the rotating commutator, means of directing the advancement of the abrasive member towards the commutator, liquid pressure means for hindering the motion of a moving part of the device, and means of mounting the device on something stationary and in position to coact with the rotating commutator.

40. A truing or grinding device, particularly for commutators, comprising an abra-

sive member, or active member, actuating means of causing the advancement of the abrasive member to cooperating contact with the rotating commutator, means of directing the advancement of the abrasive member towards the commutator, means of generating by some part of the mechanism a fluid flow, means of hindering the fluid flow, and means of mounting the device on something stationary and in position to coact with the rotating commutator.

41. A truing or grinding device, particularly for commutators, comprising an abrasive member, or active member, actuating means of causing the advancement of the abrasive member to cooperating contact with the rotating commutator, means of directing the advancement of the abrasive member towards the commutator, means of generating by some part of the mechanism a liquid flow, means of hindering the liquid flow, and means of mounting the device on something stationary and in position to coact with the rotating commutator.

42. A truing or grinding device, particularly for commutators, comprising an abrasive member, or active member, actuating means of causing the advancement of the abrasive member to cooperating contact with the rotating commutator, means for directing the advancement of the abrasive member towards the commutator, clock mechanism operatively connected to the other parts of the device to hinder motion of said parts, and means of mounting the device on something stationary and in position to coact with the rotating commutator.

Signed at New York, in the county of New York and State of New York, this 17th day of May A. D. 1928.

HORACE D. MUNDAY.
